UNITED STATES PATENT OFFICE

FRANK K. WAY, OF SPRINGFIELD, OHIO, ASSIGNOR TO JOHN FOOS, OF SAME PLACE.

ICE-SHAVING MACHINE.

SPECIFICATION forming part of Letters Patent No. 393,195, dated November 20, 1888.

Application filed October 28, 1886. Serial No. 217,474. (No model.)

To all whom it may concern:

Be it known that I, FRANK K. WAY, a citizen of the United States, residing at Springfield, in the county of Clark and State of Ohio, have invented certain new and useful Improvements in Ice-Shaving Machines, of which the following is a specification.

My invention relates to that class of ice-shaving machines which are adapted for cutting ice for the purpose of cooling drinks and for similar purposes.

It also relates in its nature to the ice-shaving machine described and shown in my pending applications filed, respectively, April 15, 1886, and April 13, 1886.

My invention consists in various constructions and combinations of parts, hereinafter described and claimed.

In the accompanying drawings, which form a part of this specification, Figure 1 is a vertical sectional elevation of a machine embodying my invention. Fig. 2 is a sectional view through the receiving-chamber D, showing the arrangement of the discharging mechanism. Figs. 3 and 4 are detailed views of the base of the same. Figs. 5 and 6 show modifications of the device hereinafter referred to.

Like parts are indicated by similar letters of reference throughout the several views.

In said drawings, A represents the base on which the machine is supported.

B is a supporting-standard, which may be of any desired form to support the frame or outer casings of the device.

The cutting mechanism consists, preferably, of a vertical disk, C, provided on the face thereof with cutting-knives a a. The cutting-disk C is preferably turned off on its periphery to fit in a bearing in which it is adapted to be revolved by a shaft, b, provided on its outer edge with a crank or handle, b'. Immediately back of the cutting-disk C is a receiving-chamber, D, provided on one side with a bearing, b'', for the shaft b. Located at the top of the revolving chamber D is a discharging device, E, adapted to be forced downward through the revolving chamber D in close proximity to the back of the cutting-disk C.

The discharging device E consists of two

plates, c c, supported, respectively, on stems 50 c' c', connected at the top by a cross-piece, c'', to the center of which is secured a knob or handle, c''. Surrounding each of the stems c' is a spring, c'', adapted to be compressed as the piston is forced downward and to return 55 the same to its former position when the pressure is removed therefrom.

The cutting mechanism, as has been stated, stands vertical in the main frame or outer casting. In order that the ice may be cut with facility, it is desirable that it be fed to the cutters at right angles thereto or in a horizontal direction. In order, however, that the ice to be cut may be readily inserted into the machine, it is desirable that the receiving-reservoir 60 open up or in a direction parallel, or substantially so, to the plane of the cutting mechanism. I accomplish this by providing a curved conduit or reservoir which extends outwardly and upwardly from the cutting mechanism, 65 preferably on the arc of a circle, a distance of about ninety degrees. This curved conduit or reservoir, which is shown at F in the drawings, is provided at the top with a suitable cover, F'. On the inside of the conduit F, 70 and adapted to reciprocate therein, is a follower, d, secured on the end of a curved stem, d', which extends through the cover F', and is preferably pivoted to a hand-lever, d''.

The ice is inserted into the conduit or reservoir, the follower d being first withdrawn by raising the hand-lever d'', as indicated by dotted lines in Fig. 1, thus raising the cover F'. The follower is then inserted against the ice in the conduit and the cover replaced. By pressing down on the hand-lever d'' the ice will be forced against the cutting mechanism, which will be set in motion by the handle b', and the chips and shavings thus formed will pass through the said cutting mechanism into the 85 receiving-chamber D. The tumbler or other receptacle into which the shavings or cuttings are to be discharged is placed under the receiving-chamber D. When the cutting mechanism is in motion, a portion of the shavings 90 will fall into the receptacle. When sufficient ice has been cut, the pressure is removed from the hand-lever d'' and the discharging device 95

E is forced downwardly through the receiving-chamber D, thus forcing the cuttings or shavings into the receptacle below.

It is obvious that the cutting mechanism may 5 be variously modified—for instance, instead of having the revolving cutting-disk mounted on the shaft which passes through the receiving-chamber, the disk may be enlarged so that the center thereof shall stand above the lower end 10 of the conduit, as shown in Fig. 7, and instead of connecting the shaft *b* directly to the handle *b'*, the power may be transmitted from the said handle through the medium of the small bevelled gears *e e*. By this construction the shaft 15 will be removed from the receiving-chamber D, the said receiving-chamber being thus left free and unencumbered, so that the discharging device E may fit snugly therein.

Instead of having a revolving cutting-disk, 20 a reciprocating cutting-disk may be used, as shown in Fig. 5, the receiving-chamber being arranged either with or without the discharging device E.

It is obvious that the handle to which the 25 power is supplied may be located either at the front or side of the machine, as desired.

The base A may be made of marble or cast in metal or other suitable material. The top of 30 the base A is constructed with a depression or 35 bowl, A', from which leads a small drip-pipe, *f*. This drip-pipe is inserted through a rubber bushing, *f'*, in the edge of the said base. By this arrangement the drip from the melted ice from the machine is collected in the top of 40 the base, and may be carried off through the drip-pipe to any convenient point of discharge, sufficient pipe being added for this purpose.

In order that the machine may be held 45 rigidly in place during the operation of cutting ice, I provide in the bottom of the base A small rubber feet *h*. These feet serve the double purpose of preventing the machine from slipping while being operated, and also prevent any marring or scratching of the counter or shelf on which it is placed.

It will be seen that by this construction a very simple and effective ice-cutting device is secured, to which the ice may be readily and easily fed, and the cuttings therefrom may be quickly and easily discharged.

Having thus described my invention, I claim—

1. The combination, with the cutting mechanism, of the conduit on one side thereof and a receiving-chamber on the other, and a reciprocating plunger for discharging the cuttings or shavings from said receiving-chamber, substantially as set forth. 55

2. The combination, with the conduit and the cutting mechanism, of the receiving-chamber at the back of said mechanism, a discharging-plunger in said receiving-chamber, and a traveling follower for forcing the ice through the said conduit against the cutting mechanism, substantially as set forth. 60

3. The combination, with the conduit and the receiving-chamber, of the cutting mechanism between said conduit and chamber and the discharging mechanism in said chamber, a hinged hand-lever above said conduit, and a follower pivoted to said hand-lever and adapted to be forced through said conduit, substantially as set forth. 65

4. The combination, with the conduit and the receiving-chamber, of a cutting-disk between said conduit and chamber, a shaft for revolving said disk journaled in a bearing in said receiving-chamber, and a discharging device adapted to be forced downward on either side of said shaft and in close proximity to 75 said cutting-disk, substantially as set forth. 70

In testimony whereof I have hereunto set my hand this 18th day of October, A. D. 1886.

FRANK K. WAY.
